Inventor:

Charles H. Wright,
By Dyerforth Dyerforth.

Atto 1888

UNITED STATES PATENT OFFICE.

CHARLES H. WRIGHT, OF CHICAGO, ILLINOIS.

BURGLAR-ALARM.

SPECIFICATION forming part of Letters Patent No. 379,144, dated March 6, 1888.

Application filed November 15, 1887. Serial No. 255,231. (No model.)

To all whom it may concern:

Be it known that I, CHARLES H. WRIGHT, a citizen of the United States, residing at Chicago, in the county of Cook and State of Illinois, have invented a new and useful Improvement in Burglar-Alarms, of which the following is a specification.

My invention relates to the class of electric burglar-alarms; and it relates more particularly to the improved means I employ for setting the device to adapt the alarm mechanism to be actuated by the movement from its position of a barrier—such as a window—to access into a room or other inclosure.

15 My invention has for its object the attainment of absolute effectiveness and reliability in its operation and simplicity of construction.

From the description hereinafter contained it will be quite evident that my improved device may be operatively applied to various forms of barriers—as doors, windows, drawers, and the like—and I do not, therefore, limit myself to any particular connection for it; but for the sake of convenience I confine the following description to its application in connection with a window, and so illustrate it in the accompanying drawings, in which—

Figure 1 shows a window in vertically-transverse sectional elevation partly broken and 30 provided with my improvement, showing the switch-finger by full lines in its position to be operated by raising the lower window-sash, and by dotted lines, respectively, in the position to close the circuit, to which position it is brought by raising the sash, and in the position to which it is moved when it is desired to maintain the device inactive; and Fig. 2, a section taken on the line 2 of Fig. 1, viewed in the direction of the arrows, and enlarged.

40 A is the inside stop, B the parting-strip, and C the outside stop, of a window-easing.

D is the lower sash, adapted, as usual, to slide between the stop A and parting-strip, and E the upper sash between the parting-strip and 45 outside stop.

On the stop A, near the upper end of the lower sash, D, when the latter is down, are provided two contact-points, r and p, one above the other, forming, through conductors q and 50 q', the terminals of a battery, F, or other form of generator, which may be located in any suit-

able position, and in the battery-circuit is a vibrating bell, G, or any other suitable sounder or alarm-producing device, which will be caused to operate by the effect upon the circuit of raising the lower window-sash. 55

H is a flat metallic finger hinged or pivoted to the lower contact-point, r, and adapted to be turned upon its support to extend, as shown, edgewise across the path of the lower sash, D, 60 or into contact with the end of upper contact-point, p, or to be turned on its pivot past or beyond the latter, each of the two latter positions being indicated by dotted lines. The first of the three positions referred to is that 65 at which the device is "set." It will be noticed that the contact-points r and p are in such position with relation to each other, the switch-finger, and sash D that when the latter is raised, while the finger H is in its path, it 70 will turn the finger into contact toward its upper end with the end of the contact-point p, thereby closing the circuit and causing the alarm to act. When it is not desired to have the device set—that is, when it is desired that 75 the alarm shall not be operative by raising the window-sash D—the finger H may be turned on the contact-point r from the contact-point p, over the end of which it slides past the latter in a direction away from the path of the 80 lower sash.

The device forming my improvement may readily be adapted by those skilled in the art to which it relates and without description or illustration in the present connection, to upper 85 window-sashes, doors, drawers, and the like, to perform its function in a manner the same or substantially the same as in the connection herein shown and described; and I therefore wish it to be understood that I intend it for 90 any such application and include the same as within the spirit of my invention.

When once placed in position, though readily removable, the device need never be disturbed for repair, as its simplicity of construction precludes the probability of impairment with use other than perhaps corrosion of the contacts or the accumulation upon them of matter that would interfere with the operation, which may, however, be readily remedied without removing the parts. 95

While it is intended that the alarm shall be 100

sounded by the closing of the circuit in the manner described through the medium of the finger H, obviously the arrangement and nature of the device could be such as to actuate 5 the alarm by opening the circuit.

What I claim as new, and desire to secure by Letters Patent, is—

In an electric burglar-alarm, the combination, with the generator, alarm mechanism, 10 and window, or the like, of two contacts, r and p, forming the terminals of the generator and located at one side of the window or the like, and beyond the actuating-edge thereof, when the latter is shut, and a switch-finger, H, piv- 15 otally connected with one of the said contacts and extending to close the circuit, with its free

end against the projecting end of the other contact, whereby it may be turned at will past such other contact away from the path of the window or the like to render the burglar-alarm 20 inoperative, and movable to extend lengthwise over the said actuating-edge of the shut window or the like, whereby opening of the latter moves the switch-finger upon its pivot into direct contact toward its free end with the end 25 of the said other contact, substantially as described.

CHARLES H. WRIGHT.

In presence of—

J. W. DYRENFORTH,
CHAS. E. GAYLORD.
